UNITED STATES PATENT OFFICE.

EDWARD C. BEERS, OF ROCHESTER, NEW YORK

RANGE.

Application filed October 7, 1920. Serial No. 415,405.

To all whom it may concern:

Be it known that I, EDWARD C. BEERS, a citizen of the United States, residing at Rochester, in the county of Monroe and 5 State of New York, have invented certain new and useful Improvements in Ranges, of which the following is a specification.

Ranges which burn solid and gaseous fuel have but a single flue under the oven bottom 10 thru which the products of combustion pass. This flue, as at present constructed in many ranges, is obstructed with one or more vertical division plates, or flue strips, which are used therein to deflect, or direct, the heated 15 gases to different parts of the flue before they reach the exit at the back of the range. These flue strips not only obstruct the flue, but form a baffle for the products of combustion and prevent their passing freely to the 20 exit, thereby heating some spots hotter than others and thus creating an unevenly heated oven bottom.

One object of my invention is the elimination 25 of division plates and flue strips in this flue under the oven bottom, thereby permitting the products of combustion to pass uninterrupted under the whole of the oven bottom to the exit into the back flue, thus heating the bottom of the oven evenly thru- 30 out.

Another object of my invention is to provide means whereby the uninterrupted flue under the entire oven bottom may be heated 35 with gases from gaseous fuel.

This and other objects of my invention will be fully illustrated in the drawings, described in the specification and pointed out 40 in the claims at the end thereof.

In the accompanying drawing:

Fig. 1 is a sectional perspective view of 45 the range.

Fig. 2 is a detail sectional perspective view of the righthand end of the range showing the dampers arranged for burning both coal and gas for the purpose of heating 50 the oven.

Fig. 3 is a front elevation of the gas water heater of the range.

Fig. 4 is a sectional view of the rear of 55 the range, the section being taken on the line 4-4 of Fig. 1.

In the several figures of the drawing, like reference numerals indicate like parts.

The body of the range is built with the fire box 1 from which the flue 2 leads over 60 the top of the oven 3. At the side of the

oven the divided flue 4 extends from the flue 1 down below the bottom of the oven where it terminates in the double flue 5. The divided flue 4 is provided with the swinging 60 partition 6 which is mounted to swing at 7 in suitable bearings in the body of the range. The double flue 5 is divided by the partition 8 which is supported at a suitable distance below and parallel with the bottom of the 65 oven 3. At the righthand end of the partition 8 is mounted the burner box 9 and vent flue 13, which form a continuation of the partition 8 and at the end of the burner box is mounted the swinging damper 10 70 which is adapted to close the open top of the burner box 9 and vent flue 13 with one side thereof and also forms an extension of the partition 8 with the other side thereof when the damper is in a horizontal position as 75 shown in Fig. 1. In the burner box 9 is mounted the burner 11 which is supplied with gas thru the intake 12, leading from the outside of the range. The burner box 9 and vent flue 13 extend from one side of 80 the range to the other side thereof and the horizontal vent flue 13 is left open at either end thereof to form a vent for the burner 11.

The oven 3 is provided with the damper 14 at the upper righthand corner thereof. 85 This damper is mounted to swing so that it can be operated by the swinging partition 6 as will hereinafter be described. At the lower lefthand corner of the oven 3 is mounted a second damper 15 which opens into the 90 exit 16 provided along the side of the left-hand wall of the oven and terminating in the back flue 17 at the rear of the range as shown in dotted lines in Fig. 1.

The exit 18 for the double flue 5 is provided below the partition 8 and the gases passing above the partition 8 must pass down thru the opening 19 at the end of the partition 8 into the lower half of the flue 5 before they pass out thru the exit 18 into the 100 rear flue 17.

When the range is operated with coal and the oven thereof is to be heated exclusively by means of the products of combustion from the coal fire in the fire box, the products of combustion from this fire pass thru the flue 2, over the top of the oven and down thru both sides of the divided flue 4 to the upper half of the double flue 5. The partition 8, vent flue 13, burner box 9 and damper 110 10 form a continuous horizontal partition that directs the products of combustion over

the full length of the upper half of the double flue, at the end of which they pass down the opening 19 into the lower half of the double flue 5 and then out thru the exit 18 into the rear flue 17. This path of the products of combustion from the fire box 1 thru the flues 2, 4 and 5, encircles the oven 3 on three sides without obstruction thereby making close contact with the three walls of the oven. In this way the highest efficiency in the heating of the three sides of the oven, is secured. The fire box 1 which is located adjacent to the oven heats the fourth side thereof while the rear flue 17 heats the back 15 of the oven.

In operating the range with coal in combination with gas for the purpose of heating the oven 3, the burner 11 is used. This burner is located in the burner box 9 and is covered by the damper 10 when coal alone is used as fuel for heating the oven, in order to prevent soot from settling thereon and keeping the holes in the burner clean. When the damper 10 is lifted from the full line position in Fig. 1 to the dotted line position thereof, the burner 11 and vent flue 13 are uncovered and the two rows of burner holes are exposed and ready to use. At the same time the lefthand end of the damper 10 makes contact with the lower end of the swinging partition 6 and in so doing, rocks the partition 6 slightly to the right. The upper end of the partition 6 is thus tilted to the left and the lug 20 formed on the upper end of the partition 6 is forced against the damper 14, which damper in turn is swung inwardly into the oven by the upper end of the partition 6. In this way a portion of the divided flue 4 is closed at the top by the partition 6 and the damper 14 is opened so that a separate flue is formed which leads from the burner 11 into the upper right-hand corner of the oven 3. When the damper 10 is moved into this position, the outer or righthand end thereof is moved down against the side of the burner box and in doing so opens into the lower half of the double flue 5 at the righthand end thereof, while the lefthand end of the damper 10 closes the upper half of the righthand end of the flue 5. The products of combustion from the fire box then pass down on the outside of the tilted partition 6 and the damper 10 directly into the lower half of the double flue 5 and out thru the exit 18 located in the rear of the lower half of the flue 5.

The gas burner 11 is provided with two rows of burner holes which are placed in such a manner that the righthand row directs its flame into the flue formed by the tilting of the partition 6 and part of the damper 10 as heretofore described. The products of combustion from this part of the burner pass, therefore, into the top of the oven thru the opening formed by the

damper 14, heating the inside of the oven, and then pass out thru the opening formed by the damper 15 into the exit 16 and out into the rear flue 17. The burner holes in the lefthand side of the burner 11 direct their flame into the upper half of the flue 5 and they in turn pass along the full length of the bottom of the oven in an unobstructed path until they reach the opening 19 therein when these products of combustion pass down into the lower half of the flue 5 and out thru the exit 18 into the rear flue 17. The path of the products of combustion from the fire box is unobstructed by either the gas burner or the parts operated in connection therewith and the products of combustion from the gas burner 11 follow an uninterrupted course without interfering with any portion of the flue thru which the products of combustion from the coal fire pass. In this way, the products of combustion from the coal fire heat the oven independently of the products of combustion from the gas burner, and the products of combustion from the gas burner heat the oven independently from the products of combustion from the coal fire, when both the coal fire and the gas burners are operated at the same time for the purpose of heating the oven. This is made possible by the use of the double flue 5 below the bottom of the oven with the exit 18 into the rear flue in the lower half of the flue 5 which keeps the products of combustion from the gas burner separate from the products of combustion from the fire box.

The partition 8 which divides the flue 5 serves to direct the products of combustion from either the gas burner or the coal fire over the full length of the bottom of the oven and this insures the even heating of this part of the oven.

The gas water heater forming part of the range, comprises the shell or "water front" 22, which is formed by a hollow casting that is divided into an upper and a lower section by the partition plate 23. On the outside of the water front are formed the ribs or fins 24 which are integral therewith. These ribs are vertically disposed on the water front and their lower end is slightly bent at an angle. Below the ribs or fins 24 is located the gas burner 25 and the flame from this burner is directed so as to impinge against the ribs or fins and the underside of the water front. The heat generated by the gas burner 25 is then absorbed by the fins 24 which heats the water front and the water circulating therein. This makes it possible to heat the water front by gas when the coal fire in the fire box 1 is low or even when no coal fire is maintained in the fire box.

I claim:

1. In a range, the combination of an oven,

a double flue at the bottom of said oven, the upper half of said double flue being connected with the lower half of said double flue, a back flue at the rear of said oven and adjacent thereto, the lower half of said double flue having an exit into said back flue.

2. In a range, the combination of an oven, a double flue at the bottom of said oven, a 10 passage between the upper half of said flue and the lower half of said flue, a second passage between the halves of said flue, means to open and close said second passage between said halves of said double flue, a 15 back flue at the rear of said oven and adjacent thereto, the lower half of said flue having an exit into said back flue.

3. In a range having a fire box, the combination of a top, side and bottom flue, a 20 movable partition in said side flue, a stationary partition in said bottom flue, said movable partition in said side flue being adapted to direct the products of combustion from the fire box either on the outside of said partition or on both sides thereof, said stationary partition being adapted to deflect the products of combustion either thru the upper or the lower half of said bottom flue.

4. In a range having a fire box and an 30 oven, the combination of a top, side and bottom flue, a stationary partition in said bottom flue, a gas burner mounted in said bottom flue, a movable partition mounted in said side flue, an inlet and an exit in said oven, said movable partition being adapted to direct the part of the products of combustion into the side of said oven and said partition being adapted to direct the other part of the products of combustion along 35 the bottom of said oven, and means to direct the products of combustion from the fire box along said bottom flue below said partition.

5. In a range having a fire box and an 45 oven, the combination of a top, side and bottom flue, a movable partition in said side flue, a stationary partition in said bottom flue, a burner box adjoining said stationary partition, a damper hinged in said bottom flue, said damper being adapted to either lengthen said stationary partition or said 50 movable partition, the products of combustion from said fire box being deflected by said damper along said bottom flue above said stationary partition when said damper

is in one position, the products of combustion being deflected by said damper along said bottom flue below said stationary partition when said damper is placed in another position.

6. In a range having a fire box and an 60 oven, the combination of a top, side and bottom flue, a movable partition in said side flue, a stationary partition in said bottom flue, a burner box adjoining said stationary flue and forming an extension thereof, a damper forming a cover for said burner box and extending to one side thereof to form an additional extension to said stationary partition, a gas burner located in said burner box, said damper being adapted 65 to uncover said burner in said burner box and join said stationary partition with said movable partition and connect the outer side of said side flue with the lower or under side of said bottom flue, said stationary partition having a passage therethru to connect the upper side with the under side of said bottom flue, and an exit from the under side of said bottom flue.

7. In a range, the combination of an oven, 70 a flue surrounding said oven at the top and bottom and one side thereof, a partition in the bottom flue dividing said bottom flue into an upper and a lower section, said partition being hollow to form a transverse 75 duct therein with openings leading into the hollow space at the front and back of said range, a gas burner mounted in said hollow section, means for opening and closing said hollow section of said bottom flue to expose 80 said gas burner.

8. In a range, the combination of an oven, a flue surrounding said oven at the top, bottom and one side thereof, a partition in said bottom flue dividing said bottom flue into an upper and a lower section, 85 said partition being partially hollow to form a transverse duct therein leading from the front to the rear of the range, a gas burner mounted in said duct, a cover provided in said partition to open said duct and expose said gas burner, said cover being adapted to close the upper section of said bottom flue at one end thereof and open 90 the end of the lower section of said bottom flue.

In testimony whereof I affix my signature.
EDWARD C. BEERS.
